[57] **CLAIM**

The ornamental design for galvanic skin resistance/temperature biofeedback device, as shown and described.

DESCRIPTION

FIG. 1 is a perspective view of the galvanic skin resistance/temperature biofeedback device; showing my new design;

FIG. 2 is a top plan view of the biofeedback device of FIG. 1;

FIG. 3 is a left side view of the biofeedback device of FIG. 1;

FIG. 4 is a rear view of the biofeedback device of FIG. 1;

FIG. 5 is a bottom plan view of the biofeedback device of FIG. 1;

FIG. 6 is a right side view of the biofeedback device of FIG. 1; and

FIG. 7 is a front view of the biofeedback device of FIG. 1.
